(57) **CLAIM**

The ornamental design for a PCB power plug connector including male and female parts, as shown and described.

DESCRIPTION

FIG. 1 is a top, front, and left side perspective view of the PCB power plug connector including male and female parts, with the male part inserted in the female part, showing my new design;

FIG. 2 is a top, front, and left side perspective exploded view thereof, with the male part removed from the female part;

FIG. 3 is a top plan view thereof, with the male part inserted in the female part;

FIG. 4 is a bottom plan view thereof, with the male part inserted in the female part;

FIG. 5 is a right side elevational view thereof, with the male part inserted in the female part, the left side elevational view being a mirror image;

FIG. 6 is a rear elevational view thereof, with the male part inserted in the female part;

FIG. 7 is a front elevational view thereof, with the male part inserted in the female part;

FIG. 8 is a top, front, and left side perspective view of the male part thereof removed from the female part;

FIG. 9 is a top plan view of the male part thereof removed from the female part;

FIG. 10 is a bottom plan view of the male part thereof removed from the female part;

FIG. 11 is a right side elevational view of the male part thereof removed from the female part, the left side elevational view being a mirror image;

FIG. 12 is a rear elevational view of the male part thereof removed from the female part;

FIG. 13 is a front elevational view of the male part thereof removed from the female part;

FIG. 14 is a top, front, and left side perspective view of the female part thereof removed from the male part;

FIG. 15 is a bottom plan view of the female part thereof removed from the male part;

FIG. 16 is a top plan view of the female part thereof removed from the male part;

FIG. 17 is a right side elevational view of the female part thereof removed from the male part, the left side elevational view being the mirror image;

FIG. 18 is a rear elevational view of the female part thereof removed from the male part; and,

FIG. 19 is a front elevational view of the female part thereof removed from the male part.

The broken lines in the Figures depict interior portions of the connector that form no part of the claimed design.
